UNITED STATES PATENT OFFICE.

DWIGHT S. CLARK, OF CAMBRIDGE, ASSIGNOR TO EMMA L. FORBES, OF BOSTON, MASSACHUSETTS.

ANGULAR PAPER BOX.

SPECIFICATION forming part of Letters Patent No. 413,029, dated October 15, 1889.

Application filed August 6, 1889. Serial No. 319,882. (Model.)

To all whom it may concern:

Be it known that I, DWIGHT S. CLARK, a citizen of the United States, and a resident of Cambridge, in the county of Middlesex and State of Massachusetts, have invented certain new and useful Improvements in Angular Paper Boxes, of which the following is a specification.

My invention relates to that class of folded paper or card-board boxes which are used for packing finely-divided substances—such as starch, oatmeal, and other foods in powder—and its object is to furnish a box which may be well and conveniently closed.

15 In Figure 1 a part of the blank designed for my box is shown, the dotted lines indicating those lines which are simply scored or indented in the usual way and not cut through. Figs. 2, 4, 7, 10, and 11 show in side elevation 20 the progressive steps in closing the end of the box. Figs. 3, 5, and 8 are front elevations of certain of these positions. Figs. 6, 9, and 12 show three of them in plan.

In Fig. 1, A, B, C, and D are designed to 25 form the sides of the box. These sides are separated from each other and form the end flaps by scored or indented lines, and the pasting-strip *p* is used to unite with paste the two sides C and D in a manner well understood, 30 so as to form a four-sided tube. This tube is shown in side elevation in Fig. 2 and from the front in Fig. 3. The end of the box is closed by the flaps *a*, *b*, *c*, and *d*, of which *d* is a full flap capable of covering the whole 35 of the end, *b* is a half-flap, while from *a* and *c* three-eighths of each are removed and five-eighths left. The two flaps last named are each divided by scored or indented lines into three triangular fields, numbered 1, 2, and 3. 40 The front half-flap *b* is differently scored, being divided into a four-sided figure in the middle and two right-angled triangles 4, 4, corresponding in size and position to identical triangles 3, 3 in flaps *a* and *c*. In closing the ends of 45 this box from the positions shown in Figs. 2 and 3 the first act is to force inward the points indicated by *x*, *x*, carrying the two triangles marked 3 and the two marked 4 inside the box and giving rise to the changes indicated 50 by the side and front elevations presented in

Figs. 4 and 5 and the views from above represented in Fig. 6. The two flaps *b* and *d* can now be inclined toward each other; or, to state it differently, if the front half-flap *b* is pressed inward it will have the effect of closing the two triangular fields 3 and 4 on each side thereof upon each other, causing the points *y*, *y* to approach, and the triangular fields 2, 2 to lie down, and the large back flap *d* to come forward and take an inclined position, the condition of things being clearly represented in the side and front views shown in Figs. 7 and 8 and in the plan, Fig. 9. A further pressure on *d* will at once give to the end the appearance seen in the side elevation, Fig. 10, and then close it altogether, as in Figs. 11 and 12.

Fig. 13 is a modified form of blank, differing from that shown in Fig. 1 only by the omission of the scored lines *y*, *r* and *y*, *s*. In this case the several steps selected to explain the process of closing are shown in side elevation in Figs. 14, 16, 19, 21, and 24, and in front elevation in Figs. 17, 20, 22, and 25, and in plan in Figs. 15, 18, 23, and 26. The folding of this modification of my box is then as follows: The strip *p* is first pasted on the inner surface of *D*, giving the open quadrilateral tube shown in side elevation in Fig. 14 and in plan in Fig. 15. The fields of the side flaps *a* and *c* (now marked 5 in Fig. 13) are next inclined toward each other, which causes the back flap *d* to incline inward and the front flap *b* to incline in the same direction—that is, to fall out from the body of the box—as is shown in the views, Fig. 16 from the side, Fig. 17 from the front, and Fig. 18 from above. When the full flap *d* is further depressed, the fields 5, 5 descend also and draw back the front flap *b*. This change is illustrated by Figs. 19 and 20. The next step consists in pressing the flap *b* back until it passes under the large descending flap *d*, and takes for a moment in passing the position shown in Fig. 21 a side elevation, Fig. 22 a front elevation, and Fig. 23 a plan view, of the nearly-closed box. Fig. 24 is the position reached just before the flaps all lie flat, which final state of things is seen in front elevation in Fig. 25 and in plan in Fig. 26.

The differences in the closed end resulting from the blank represented in Fig. 1 and that from the blank marked 13 are chiefly to be found in the formation of two little wings, 5 each consisting of the triangular fields 3 and 4, face to face and extending downward. By the material packed in the box or otherwise these wings may be thrust up flat against the end and toward the front B or not, as de-10 sired; but in the case of the box from the blank shown in Fig. 13 the fact that the lines $y\ r$ and $y\ s$ are not scored and that the whole field 5 is stiff in consequence causes the folds which correspond to the wings aforesaid to 15 remain always thrust up and flat, reaching to the front side B and in contact with the end. This in many cases may be regarded as an advantage; but the box is not folded as easily as when the blank in Fig. 1 is used, 20 nor is the surface formed by the closed flaps, upon which the large back flap d lies, quite as flat as it is when the middle four-sided figure in b and the fields 2 2 come edge to edge. As a consequence the pasting up should be care-25 fully done. It will frequently be found convenient to construct one end of the box so as to close in the manner provided for in Fig. 1 and the other end as in Fig. 13, the former to be pasted up first and the latter after the 30 material which is to fill the package is in place.

By the expression a "full" or "full-sized" flap used in this specification, a flap is meant the width of which is equal to the width of 35 that side of the box to which it is attached and the height or length of which is equal to the least width of the box itself.

Having described my invention, what I claim, and desire to secure by Letters Patent, 40 is—

1. A blank for an angular paper box, scored or indented for folding, so as to form the sides A, B, C, and D, and the pasting-strip p , the

full back flap d , the half front flap b , subdivided to form a trapezoidal figure, and two 45 triangles 4 4 at the ends thereof, with two side flaps, each subdivided to form the triangular fields 1, 2, and 3, substantially as de-50 scribed.

2. A blank for an angular paper box, scored 50 or indented for folding to form the sides A, B, C, and D, and the pasting-strip p , all connected together, and the four flaps a , b , c , and d , to form the end, all connected together and to the sides, of which one is a full flap, one 55 a half-flap provided with two triangular fields at its sides, as shown, and two five-eighths flaps placed alternately and subdivided into three triangles, as set forth, substantially as 60 described.

3. An angular paper box consisting of the sides A, B, C, and D, united to form a four-sided prism and closed by ends constructed each of the side flaps a and c folded in part upon themselves and in part against two 65 equal folds of the front flap, of the remainder of said front flap, and of a large back flap covering the whole end of the box and all the flaps below it, substantially as described.

4. An angular paper box consisting of the 70 sides A, B, C, and D, united to form a four-sided prism and closed by ends composed of, first, the adjacent triangular fields 2 and 3 of each of the side flaps in contact, respectively, with the triangular fields 1 1 of the 75 same flaps and 4 4 of the front flap, with the remainder of the front flap laid flat upon the fields 4 4, and the folded side flaps, a full-sized back flap covering the whole and joined to fields 1 1 of said side flaps, substantially as 80 described.
